HOUSING FOR AN ALARM CLOCK OR THE LIKE

Richard K. Thomas, Elk Grove Village, Ill., assignor to
Sunbeam Corporation, Chicago, Ill.

Filed July 5, 1974, Ser. No. 486,026

Term of patent 14 years

Int. Cl. D10—01

U.S. Cl. D10—23

Fig. 1.

Fig. 2.

Fig. 3.

Fig. 4.

Fig. 5.

Fig. 6.

Fig. 7.

FIG. 1 is a front elevational view of a housing for an alarm clock or the like showing my new design;

FIG. 2 is a right side elevational view thereof, the left side being a mirror image thereto;

FIG. 3 is a rear elevational view thereof;

FIG. 4 is a top plan view thereof;

FIG. 5 is a front elevational view of another embodiment of my new design of FIG. 1 wherein the top button has been omitted;

FIG. 6 is a right side elevational view of FIG. 5, the left side being a mirror image thereto;

FIG. 7 is a top plan view of FIG. 6.

I claim:

The ornamental design for a housing for an alarm clock or the like, as shown and described.
